US0D1023878S

(12) **United States Design Patent** (10) Patent No.: **US D1,023,878 S**
(45) Date of Patent: ** Apr. 23, 2024

(54) **ADJUSTABLE COCKPIT FOR VEHICLES**

(71) Applicant: **LG ELECTRONICS INC.**, Seoul (KR)

(72) Inventors: **Byungkyu Kim**, Seoul (KR); **Hansoo Kim**, Seoul (KR); **Byunglok Jeon**, Seoul (KR); **Inkoo Shim**, Seoul (KR); **Diboine Romain**, Seoul (FR)

(73) Assignee: **LG ELECTRONICS INC.**, Seoul (KR)

(**) Term: **15 Years**

(21) Appl. No.: **35/517,565**

(22) Filed: **Jun. 21, 2022**

(80) **Hague Agreement Data**

Int. Filing Date: **Jun. 21, 2022**

Int. Reg. No.: **DM/222236**

Int. Reg. Date: **Jun. 21, 2022**

Int. Reg. Pub. Date: **Jun. 23, 2023**

(30) **Foreign Application Priority Data**

Jan. 27, 2022 (KR) 30-2022-0004032
